UNITED STATES PATENT OFFICE.

ALEXANDER BRADFORD, OF RAYNHAM, MASSACHUSETTS.

IMPROVED ANCHOR.

Specification forming part of Letters Patent No. 41,754, dated March 1, 1864.

To all whom it may concern:

Be it known that I, ALEXANDER BRADFORD, of Raynham, in the county of Bristol and State of Massachusetts, have invented new and useful Improvements in Ship's Anchors; and I do hereby declare that the following is a full and complete description thereof, reference being had to the accompanying drawings, making a part of this specification, in which—

Figure 1 is a view of the anchor herein described; Fig. 2, a view of one set of flukes, and Fig. 3 a view of one set of the palms.

The improvement in this invention may more fully be shown by comparing the method of manufacturing anchors in common use with the manufacture of this one.

The present method of manufacturing anchors is to forge the shank, the flukes, and the palms from separate pieces of iron, and then to weld the palm upon the fluke, and the fluke to the shank; but in the making of anchors shown in these specifications welding is done away with entirely.

The shank A is made of the desired dimensions, with a head forged upon the lower end, as shown at B. Each pair of flukes are of one solid piece of iron, and the palms are forged upon the ends, not welded. When thus forged they are as shown in Fig. 2. Two sets of these flukes are riveted to the shank—one set on each side thereof—immediately above the head, with the flukes resting upon it, so that a large proportion of the strain, when in use, shall come against and be borne by the head B.

The palms of anchors in common use are nearly heart-shaped, thus leaving deep shoulders on the side where they are welded to the flukes, into which shoulders the cable is liable to become entangled; but in this the

palms are forged tapering on the inner as well as the outer sides, not leaving any shoulder to foul the cable.

I believe the improvements in this invention to be: First, the use of four flukes—two on each side of the shank—instead of two, without materially increasing the amount of iron used, in comparison with other anchors of the same capacity; second, the palms being forged upon the ends of the flukes are not so liable to be broken off; third, being of the particular shape shown—that is, tapering toward the fluke, as well as from it, they are not liable to foul the cable; fourth, being double, or in pairs, the two palms together present a larger surface against the earth, when buried in it, and consequently more effectually prevent the vessel from dragging; fifth, the flukes being fastened to the shank, against the head, by rivets, and assisted by the two braces D D, also riveted to the flukes at E E, its power to resist a strain is greater; sixth, by the use of two palms they may be made sharper or more pointed, and consequently will enter the ground more easily.

What I claim as my invention, and desire to secure by Letters Patent, is—

1. The shank A, having a head, B, forged upon it.
2. The two sets of flukes, C C, fastened to the shank by rivets, and supported by the braces D D, substantially as here shown.
3. The palms F F, substantially of the same shape as here shown, for the double purposes of entering the ground easily and of not fouling the cable, as above set forth.

ALEXANDER BRADFORD.
